CLAIM

The ornamental design for a reference station for robotic mower, as shown and described.

DESCRIPTION

FIG. 1 is a perspective view of a reference station for robotic mower showing our new design;

FIG. 2 is a back view of FIG. 1 thereof;

FIG. 3 is a front view of FIG. 1 thereof;

FIG. 4 is a left side view of FIG. 1 thereof;

FIG. 5 is a right side view of FIG. 1 thereof;

FIG. 6 is a top view of FIG. 1 thereof; and,

FIG. 7 is a bottom view of FIG. 1 thereof.

The broken line showing on the surface of the claim in FIGS. 1-7 is included for the purpose of illustrating portions of the reference station for robotic mower and forms no part of the claimed design.
